UNITED STATES PATENT OFFICE.

MILTON M. DRYFOOS, OF NEW YORK, N. Y.

WEARING-APPAREL.

1,079,041.

Specification of Letters Patent. Patented Nov. 18, 1913.

Application filed May 31, 1913. Serial No. 770,957.

To all whom it may concern:

Be it known that I, MILTON M. DRYFOOS, a citizen of the United States, residing at New York, in the county of New York and State of New York, have invented a certain new and useful Improvement in Wearing-Apparel, of which the following is a specification.

This invention relates generally to wearing apparel, and particularly to underskirts or petticoats for women, and it has among its objects to provide a ready made garment comprising an elastic top portion, an inelastic lower portion, and having a waistband composed of elastic and inelastic material, said garment being adapted, when it leaves the factory, to fit waists of different sizes without the necessity of making any change or alteration of any kind in the waistband thereof, and to produce such a garment without the use of special expensive machinery, and it consists in the parts and combinations of parts hereinafter described and claimed.

In the accompanying drawings forming a part of this specification, Figure 1 is a perspective view of the upper part of my improved garment. Fig. 2 is a rear elevation of the same. Fig. 3 is a detail view of the upper portion of the garment showing the waistband and placket.

Similar letters refer to similar parts throughout all the views.

Referring to the drawings A represents the skirt or garment the top or body portion thereof being made of the elastic material commonly known as Jersey cloth with the exception of the gussets B, which are inserted at the back or rear of the garment and in which the placket is formed, said gussets being of inelastic material. The gussets extend to the waistband C and form a portion or section thereof while the inner facing, *a*, of the waistband is also formed of inelastic material. The outer facing *b* of the waistband is formed by folding the top edge of the elastic body portion and stitching the same to the inelastic part or section *a* of the band in the usual manner.

The outer facing *b*, however, does not extend the length of the waistband but terminates at the point *c*, at each side, where the elastic material joins the gussets. The sections of the waistband formed by the gussets are covered by elastic straps D, said straps being laid on the gussets with one end

folded over and the other end inserted between the end of the inner facing and the gussets. The elastic strap D is stretched and held in that condition while being stitched to the gussets along their top and bottom edges so that upon release the elastic strap contracts and forms the plaits or gathers E in the top of the gussets. The stitching connecting the gussets and the elastic strip is continued through the folded ends of the straps so as to insure their retention in place. The folded ends of the elastics insure greater strength, and said folded ends are pierced by the stems of the fastening devices, *c*, used to fasten the waistband, such fastening devices being preferably of the type known as glove fasteners. Similar fasteners are used to close the placket openings. The use of the inelastic gussets greatly strengthens the skirt at the point where the greatest strain occurs in use--namely, at the back caused by the strain across the hips and at the waistband--and renders the garment more durable. Their use also prevents the bottom of the placket opening tearing apart as frequently occurs in skirts in which the upper part is made of Jersey or similar goods.

I am aware that skirts having hip portions made entirely of Jersey cloth and provided with an elastic silk ribbon forming the waistband; and also that waistbands formed of an elastic stitched to and entirely inclosed in a skirt of inelastic material are old, and I do not claim such constructions.

The manufacture of my improved skirt does not require skilled labor, nor special machinery. And a skirt having a waistband of a normal measurement of twenty-two inches as it leaves the factory may be readily worn by a woman having a waist measuring twenty-six or twenty-seven inches without any alteration whatever. Also it will be observed that should the elastic lose its elasticity before the garment wears out it may be readily replaced with new elastic at small expense and the least trouble.

What I claim is:

1. A skirt comprising a body portion of elastic material provided with a gusset of inelastic material having a placket opening formed therein.

2. A skirt having an elastic body portion, a waist band composed of an elastic section

and an inelastic section, and a gusset of inelastic material having a placket opening formed therein.

3. A skirt comprising an elastic body portion, a waistband having an inelastic portion to which said body portion is secured, a gusset of inelastic material inserted in said body portion and forming a section of the waistband, and elastic straps

stitched to the waist band section of the 10 gusset by longitudinal lines of stitching.

In testimony whereof, I affix my signature, in the presence of two witnesses.

MILTON M. DRYFOOS.

Witnesses:
